CLAIM

The ornamental design for a sealed fluid container, as shown and described.

DESCRIPTION

FIG. 1 is a front-left perspective view of a sealed fluid container according to the new design;

FIG. 2 is a rear view thereof;

FIG. 3 is a front view thereof;

FIG. 4 is a left view thereof;

FIG. 5 is a right view thereof;

FIG. 6 is a top view thereof; and,

FIG. 7 is a bottom view thereof.
